Primary Examiner — John Windmuller*Assistant Examiner* — John R Yeh(74) *Attorney, Agent, or Firm* — Smith Risley Tempel Santos LLC; Gregory Scott Smith(57) **CLAIM**

The ornamental design for a mop head, as shown and described.

DESCRIPTION

FIG. 1 is a perspective view of the of my new ornamental design of a mop head shown in the environment of a mop handle;

FIG. 2 is an exploded view of my ornamental design;

FIG. 3 is a bottom angle perspective view of my ornamental design;

FIG. 4 is a top plan view of my ornamental design;

FIG. 5 is a bottom plan view of my ornamental design;

FIG. 6 is a front elevation view of my ornamental design;

FIG. 7 is a rear elevation view of my ornamental design;

FIG. 8 is a right side elevation view of my ornamental design; and,

FIG. 9 is a left side elevation view of my ornamental design. The broken lines throughout the various figures form no part of the claim and the handle, illustrated with broken lines is provide for environmental reference and does not form any part of the claim. The shading on the two strips on the bottom of the mop head as illustrated in FIG. 3 and in FIG. 5 is to illustrate that the texture of the two strips is different than the texture of the remainder of the bottom.
